SELF LOCKING JIB SLIDE

Vincent Kanser, 59 Forest Ave., Glen Ridge, N.J.
Filed Nov. 21, 1960, Ser. No. 70,797
7 Claims. (Cl. 114—108)

The present invention relates to marine hardware and, more particularly, to an improved self locking jib slide.

Heretofore, the luff (or forward leach) of a jib was slidably attached to a stay wire or rope (extending from the bow eye to the upper portion of the mast) by conventional jib slides which were secured to the bolt rope or bolt wire reinforced edge of the jib and which were slidable in the stay wire or rope.

Recently the reinforcing bolt ropes (which rot) and the reinforcing bolt wires (which rust) for the jib have been eliminated. The edge portions of the jib are now reinforced with a cloth tape, such as a nylon, Orlon or Dacron tape. This cloth tape covers both sides and is sewed to the edge portion of the jib.

Nylon is the generic or common name for a series of polyamide resins made by the polymerization of the hexamethylenediamine salt of adipic acid. Orlon is a registered trademark owned by E. I. du Pont de Nemours & Co., Wilmington, Del. and is a synthetic fiber made principally from polyacrylonitrile. Dacron is a registered trademark owned by E. I. du Pont de Nemours & Co., Wilmington, Del. and is a synthetic fiber made by the condensation of dimethyl terephthalate and ethylene glycol.

A general object of the present invention is the elimination of the difficulties and defects of the conventional jib slides by the provision of an improved jib slide which is adapted for permanent attachment to a tape reinforced edge portion of the jib; which will not tear loose from such edge portion of the jib; and which can be quickly and economically attached to the edge portion of the jib.

Another object of the present invention is the provision of an improved jib slide which is self locking and will not become detached from the stay wire unless such improved jib slide is manually removed therefrom.

The aforesaid objects of the present invention and other objects which will become apparent as the description proceeds are achieved by the provision of an improved jib slide having a first leg disposed on one side of the edge portion and provided at one end with a first hook extending beyond the edge portion, a second leg on the other side of the edge portion and provided at one end with a second hook in abutting engagement with the first hook. The second leg crosses over the first leg to lock the hooks together. The legs are provided at their other ends with means for securing the legs to the edge portion.

For a better understanding of the present invention reference should be had to the accompanying drawing, wherein like numerals of reference indicate similar parts throughout the several views and wherein:

FIG. 1 is a side elevational view of the improved jib slide of the present invention shown in position on a tape reinforced edge portion of a jib preparatory for attachment thereto;

FIG. 2 is another side elevational view of the jib slide shown in FIG. 1, along the line II—II of FIG. 1 in the direction of the arrows;

FIG. 2A is a fragmentary enlarged side elevational view, similar to FIG. 2, of the lower portion of FIG. 2;

FIGS. 3, 4 and 5 are fragmentary views, similar to FIG. 1, of alternative hook structures;

FIG. 4A is an enlarged fragmentary perspective view to show greater detail of the embodiment of FIG. 4;

FIGS. 6 and 7 are views similar to FIG. 1 of alternative embodiments of the jib slide;

FIG. 8 is a fragmentary view, similar to a portion of FIG. 7, showing another embodiment of fastening means for the jib slide shown in FIG. 7;

FIG. 9 is a side elevational view of a further alternative embodiment of the jib slide;

FIG. 10 is a side elevational view of the jib slide shown in FIG. 9, along the line X—X of FIG. 9 in the direction of the arrows.

With specific reference to the form of the present invention illustrated in the drawing, and referring particularly to FIGS. 1 and 2, an improved jib slide of the present invention is designated by the reference numeral 90, which jib slide 90 is shown positioned on a tape reinforced edge portion 92 of a jib preparatory for attachment thereto. This jib slide 90 is formed from a single piece of rigid but resilient metal wire or rod, suitably stainless steel.

A first hook leg 94f (FIGS. 1, 2 and 2A) carrying a first hook 96f on its outer end is disposed on the front side 20 of the edge portion 92 and extends diagonally inward, terminating in the left-hand side (FIG. 1) of a first eyelet 98f. The first hook 96f extends beyond an edge 99 of the edge portion 92. A first U-leg 100f of a U-shaped central support member extends from the right side (FIG. 25) 1) of the first eyelet 98f and terminates in the right hand side of an arcuate portion 102 of the U-shaped central support member, which arcuate portion 102 crosses over and supports the edge 99 of the edge portion 92. Such edge portion 92 is seated in the arcuate portion 102. 30 A second U-leg 100s extends (on the rear side of the edge portion 92, FIG. 1) from the left-hand side of the arcuate portion 102 and terminates in the left-hand side (FIG. 1) of a second eyelet 98s. As shown in FIG. 1, a second hook leg 94s extends diagonally from the right hand side of the second eyelet 98s to the edge 99; crosses over the first hook leg 94f but on the opposite side of edge portion 92; and carries a second hook 96s, which second hook 96s is disposed in abutting engagement with the first hook 96f and is oppositely directed with respect to said first hook 96f. Because the hook legs 94f and 94s cross over each other (as viewed in FIG. 1), they may be said to be in criss-cross relation.

In order to secure the jib slide 90 to the edge portion 92, conventional fastening means, such as a screw or bolt 45 means, suggested at 91, is inserted through the first eyelet 98f, the edge portion 92 and the second eyelet 98s, with attendant aligning of and locking together of the eyelets 98f and 98s as a fixed spring pivot.

It will be noted from a consideration of FIG. 1 that the 50 first hook leg 94f and the second hook leg 96s cross over each other (in this case on opposite sides of the edge portion so that the hooks 96f and 96s carried thereby are spring-biased or locked together). As a result, once a stay wire (not shown) is disposed within the hooks 96f and 96s, such stay wire (not shown) cannot become unattached from the hooks 96f and 96s unless manually removed therefrom.

To facilitate insertion of the stay wire (not shown) into the hooks 96f and 96s, the lower inner side wall of each 60 hook 96f and 96s is provided with a guide level, which guide bevels comprise a guide aperture 104.

Alternatively, to simplify the jib slide 90, the U-shaped central support member comprising the U-legs 100f and 100s and arcuate portion 102 may be dispensed with.

In order to provide alternative guide means for the introduction of the stay wire (not shown) between spring locked hooks 96f' and 96s', lower ends 106f' and 106s' (FIG. 3) of the hooks 96f' and 96s', are bent outwardly to provide an enlarged V-shaped guide aperture 104a.

Alternatively, as shown in FIG. 4, the terminal portions 108f'' and 108s'' of the hooks 96f'' and 96s'' may be extended and bent inwardly toward the associated

adjacent hook. The ends of the terminal portions 108f" and 108s" are provided with a circular end slot (of the same diameter as the wire or rod of which the jib slide 90 is fabricated) so that such terminal portions 108f" and 108s" will receive the associated adjacent hook. This arrangement shown in FIG. 4 provides a suitable guide aperture 104b. To assemble the hooks 96s" and 96f" to a cable, these hooks are spread apart against resiliency of legs 94s and 94f, thereby permitting terminal portions 108f" and 108s" to separate from their seated relation so that the cable may be passed into and be received by the hooks.

In order to provide still further locking means for hooks 96f" and 96s", the free end of each hook may be extended, as shown in FIG. 5, and bent in the generally sinusoidal shape (shown in such FIG. 5) to form locking tabs 108f"" and 108s"" which tabs 108f"" and 108s"" are biased against the respective hook legs 94f"" and 94s"".

Alternative Embodiments of the Jib Slide

In FIG. 6, a jib slide 90c has a first eyelet 98f disposed on the front side of the edge portion 92. A first hook leg 94f extends from the left hand side of the eyelet 98f diagonally to the edge 99 of the edge portion 92 with the first hook 96f disposed in its usual position. A second hook leg 94s' extends from the right side of the first eyelet 98f; is inserted through an aperture 101 in the edge portion 92; and extends diagonally (on the back side of the edge portion 92 to the edge 99 where the second hook 96s is in abutting and spring locking relationship with the first hook 96f). As described for FIGS. 1 and 2, the legs 94f and 94s cross each other (are criss-crossed) so that spring-locking of the hooks 96f-96s is facilitated. Conventional fastening means (such as a bolt or screw, not shown) is inserted through the eyelet 98f and the edge portion 92 to secure the jib slide 90c to the edge portion 92. An advantage of this construction is that the hooks 96f and 96s are disposed closer to the edge 99 of the edge portion 92, since the U-shaped central support member (of FIGS. 1 and 2) is not employed.

As shown in FIG. 7 (and in a jib slide 90d shown therein), the hook legs 94f" and 94s" are crossed on the same side of the edge portion 92 (in this case the front side). In order that the hook legs 94f" and 94s" will be disposed in substantially the same plane, one of the hook legs, for example the second hook leg 94s", is provided with a saddle or generally U-shaped central portion 110 for receiving the hook leg 94f" and for providing a spring pivot at 112. The upper portions of the hook legs 94f" and 94s" are bent over an aperture in the jib (or a grommet 114) and leg extensions 113f and 113s thereof extend diagonally to, and beyond, the edge 99 (on the other side) of the edge portion 92. An extending U-shaped terminal portion 116 (of the single wire or rod from which the jib slide 90d is formed) is then bent back over the edge 99 and against the edge portion 92 (backed up by the leg extensions 113f and 113s). Use of the hook structure shown in FIG. 4 is effective to increase the spring locking force on the hooks 96f and 96s.

Alternatively, as shown in FIG. 8, the leg extensions 113f' and 113s' may terminate in an eyelet 115, which eyelet 115 is disposed short of the edge 99 to permit use of either conventional fastening means (such as a bolt or screw, not shown) through the edge portion 92 and eyelet 115 or use of sewing with cord to attach the jib slide 90d' to the edge portion.

As shown in FIGS. 9 and 10, a jib slide 90e, similar to jib slide 90d (FIGS. 7 and 8), may be made from metal strip. A hook leg 94e carrying a hook 96e is disposed on one side (i.e. the back side, FIGS. 9 and 10) of the edge portion 92, and terminates (at the opposite end to the hook 96e) in an arcuate portion 117 which straddles either an aperture in the edge portion 92 or the grommet 114. A leg extension 113e extends diagonally

from the arcuate portion 117 down the other (or front) side of the edge portion 92 and beyond its edge 99. A terminal portion 116e of the leg extension 113e is bent over the edge portion 92 to lock the jib slide 90e in place.

5 To provide locking means for the hook 96e, its free end is provided with a locking tab 108e, similar to the locking tabs 108 shown in FIG. 5.

10 It will be appreciated that alternatively the leg extension 113e can be terminated short of the edge 99 and such leg extension 113e provided with an aperture 118 (FIG. 9). Such leg extension 113e is then secured to the edge portion 92 by either sewing the aperture 118 to such edge portion 92 or by inserting conventional fastening means (such as a bolt or screw, not shown) through the aperture 118 and the edge portion 92.

15 It will be recognized by those skilled in the art that the objects of the present invention have been achieved by the provision of an improved jib slide which can be quickly, permanently and economically affixed to a tape reinforced edge portion of a jib. Such improved jib slide will not tear loose from the jib and permanently locks the associated stay wire to the jib slide.

20 While in accordance with the patent statutes a preferred embodiment of the present invention has been illustrated and described in detail, it is to be particularly understood that the invention is not limited thereby.

I claim:

1. In combination, a sail including a reinforcement extending along one edge thereof, and a jib slide of stiffly resilient material attached to said sail at said edge, said slide comprising first hook leg means disposed on one side of a portion of said edge and including a first hook disposed beyond said edge portion, second hook leg means integrally connected to said first hook leg means and disposed on the other side of said edge portion in criss-cross relation to said first hook leg means and including a second hook disposed beyond said edge portion and in registry and in resiliently stressed abutting engagement with said first hook, the connection between said first and second hook leg means defining an eyelet portion in a plane at a right angle to the plane of said hooks, and fastening means extending through said eyelet portion and said edge portion for securing said jib slide to said edge portion, wherein each of the free ends of said first hook and said second hook is bent inwardly toward the adjacent hook to receive said adjacent hook and to provide a guide aperture between said first hook and said second hook.

2. In combination, a sail including a reinforcement extending along one edge thereof, and a jib slide of stiffly resilient material attached to said sail at said edge, said slide comprising first hook leg means disposed on one side of a portion of said edge and including a first hook disposed beyond said edge portion, second hook leg means integrally connected to said first hook leg means and disposed on the other side of said edge portion in criss-cross relation to said first hook leg means and including a second hook disposed beyond said edge portion and in registry and in resiliently stressed abutting engagement with said first hook, the connection between said first and second hook-leg means defining an eyelet portion in a plane at a right angle to the planes of said hooks, the criss-cross relation of said first and second hook leg means occurring on opposite sides of said reinforcement at a location between said eyelet portion and said edge, and fastening means extending through said eyelet portion and said edge portion for securing said jib slide to said edge portion.

3. The jib slide recited in claim 2 wherein said first hook and said second hook are provided with a guide aperture at the entrance to their abutting surfaces.

4. The jib slide recited in claim 2 wherein the outer end of said first hook and said second hook is bent outwardly from the abutting surfaces of said hooks to provide a guide aperture.

5. The jib slide recited in claim 2 wherein each of the free ends of said first hook and said second hook is provided with a leaf spring locking tab engageable with an associated hook leg.

6. The jib slide recited in claim 2 wherein fastening receiving means comprises a first eyelet disposed on said one side and connected to said first hook leg, a second eyelet disposed on said other side and connected to said second hook leg, and a U-shaped central supporting member connected to said first eyelet and said second eyelet.

7. The jib slide recited in claim 2 wherein fastening receiving means comprises an eyelet disposed on said one

side and connected to said first hook leg and said second hook leg, and said second hook leg passes through said edge portion to said other side at a point between its connection to said eyelet and said second hook.
